UNITED STATES PATENT OFFICE

157,427

MOTORCYCLE BUMPER

Claude Powers, Dayton, Ohio

Application May 14, 1947, Serial No. 139,030

Term of patent 3½ years

(Cl. D90—1)

To all whom it may concern:

Be it known that I, Claude Powers, a citizen of the United States, residing at Dayton, Montgomery County, Ohio, have invented a new, original, and ornamental Design for a Motorcycle Bumper, of which the following is a specification, reference being had to the accompanying drawing, forming a part thereof, in which—

Fig. 1 is a perspective view of a motorcycle bumper embodying my new design a portion thereof being broken away for convenience of illustration, and

Fig. 2 is a side view thereof.

The dotted line showing of Fig. 2 is for illustrative purposes only.

I claim:

The ornamental design for a motorcycle bumper, substantially as shown and described.

CLAUDE POWERS.
